VENTILATED RUBBER CUSHION HEEL PAD

William J. Dwyer, San Francisco, Calif.

Application November 25, 1935, Serial No. 51,419

1 Claim. (Cl. 36—3)

My invention relates to improvements in ventilated rubber cushion heel pads, and it consists of the combinations, constructions and arrangements hereinafter described and claimed.

5 An object of my invention is to provide a ventilated rubber cushion heel pad which is placed in a recess hollowed out in the heel of a standard shoe. The recess is preferably provided with a portion of a spherical surface 10 and extends through the inner and outer soles and down into the heel portion of the shoe. The device itself is made from resilient material such as rubber, and has an under surface conforming with the spherical surface of the 15 recess. The upper surface is provided with a slight depression, and if desired the heel pad of the shoe may be cemented to the upper surface.

One of the principal features of the invention 20 is the provision of grooves in the under surface of the pad, these grooves crossing each other and cooperating with the wall of the recess for providing air conduits. During the walking operation the pad is alternately compressed 25 and expanded, and this will create an alternate compression and suction within the conduits whereby air is forced out and sucked into the space between the pad and the heel, thereby keeping the pad cool.

30 The principal weight of the person is borne by the heels, and the pad is placed directly beneath the heels so that a resilient support will be afforded. The device is extremely simple in construction, and can be quickly added 35 to a standard shoe with but a slight alteration being necessary in the latter. The recess in the heel is formed in the center of the heel, and therefore it does not interfere with the nails or other fastening means used for securing the heel to the shoe, since these fastening means are disposed adjacent to the marginal edges of the heel.

Other objects and advantages will appear in 40 the following specification, and the novel features of the device will be particularly pointed out in the appended claim.

45 My invention is illustrated in the accompanying drawing forming a part of this application, in which—

50 Figure 1 is a side elevation of a standard shoe shown partly in section, and illustrates how the rubber cushion is disposed in the heel recess;

55 Figure 2 is a plan view of Figure 1 and illustrates in dotted lines the position of the rubber cushion; and

Figure 3 is a perspective view of the rubber cushion and heel pad shown in inverted position.

In carrying out my invention I have illustrated the rear portion of a standard shoe indicated 5 generally at 1, and this shoe is provided with an inner sole 2, an outer sole 3, and a heel 4. A recess 5 is cut into the inner sole 2, the outer sole 3, and down into the heel 4. This recess has its lower surface shaped as a portion 10 of a sphere which lower surface is bounded by a vertical circular rim, and the recess is positioned in the shoe so as to lie directly below the heel of the wearer.

The rubber cushion is shown at 6 in Figure 1. 15 This cushion has an under surface 7, see Figure 3, that has the same spherical shape as the recess 5. The rubber cushion has an edge 13 designed to contact with the rim of the recess 5. The under surface 7 is provided with two 20 grooves 8 and 9 that intersect each other at right angles as shown in Figure 3. The upper surface 10 of the rubber cushion is hollowed out slightly, and if desired a heel pad 11 may be cemented thereto. Figure 1 shows the heel 25 pad extending beyond the circular edge of the cushion. The heel pad is preferably made of leather.

From the foregoing description of the various parts of the device, the operation thereof may 30 be readily understood.

As already stated, the device can be attached to any standard shoe. The recess 5 is formed in the shoe as described and shown, and then the rubber cushion is placed in the recess and 35 the heel pad will overlie the cushion and a portion of the inner sole. When the cushion 6 is not supporting the weight of the wearer, the rim 13 will have its upper portion projecting above the top of the inner sole. When the 40 cushion 6 supports the wearer it will be depressed until its upper surface lies substantially flush with the top of the inner sole. The cushion 6 will compress under the weight of the wearer because the cushion is made of rubber. 45 The grooves 8 and 9 aid in permitting the cushion to be depressed into the recess 5 because they provide space for receiving the under surface 7 as it is enlarged during the actual compressing of the cushion. The rim 13 contacts 50 with the rim of the recess during the depressing of the cushion and prevents the dislodgement of the cushion from the recess.

During the walking operation the person's heel will compress the cushion as a step is 55

being taken, and this will partially collapse the walls of the grooves 8 and 9, and drive air from these grooves and out beneath the heel pad. At the end of the step the person's heel pad 5 is lifted away from the pad or cushion 6, and this will permit the cushion to resume its normal shape. The walls of the grooves 8 and 9 will also return to normal position and a suction will be created in the grooves which will 10 draw in additional air from around the heel pad 11, and this air will flow into the grooves 8 and 9. The result will be a pulsating flow of air beneath the rubber cushion, and this flow of air will have a cooling effect on the device 15 and prevent it from becoming overheated through use. It should be noted that air is free to pass between the inner sole 2 and the heel pad 11 during the pulsation of air beneath the heel pad. The grooves 8 and 9 therefore 20 perform the double function of acting as air conduits and also affording space for receiving the compressed cushion when a person's weight is placed on the cushion. The edge 13 of the cushion riding against the rim of the recess 5 25 acts in much the same manner as a piston in a cylinder. The recess rim guides the cushion rim as the cushion is alternately compressed and expanded during the walking operation. The cushion rim at all times contacts with 30 the recess rim and prevents the cushion from being forced out of the recess.

When a person is standing his heels will rest directly on the rubber cushions, and there will be a more resilient support afforded than 35 is possible with a standard shoe. The feet will therefore not become tired as quickly and in this way the device lessens fatigue.

The device can be removed at will, and repaired or a new device substituted, and this can 40 be done without the need of any special tools.

etc. As already stated the recess 5 is formed to enter the center of the heel 4, and therefore the fastening means such as nails 12 will not be interfered with since these nails are disposed near the edge of the heel 4.

I am well aware of cushions being placed in a shoe but these are disposed on top of the inner sole, and throw the entire foot out of alignment because they raise the heel above the place it should occupy in the shoe. I am 10 not aware, however, of a ventilated heel cushion disposed in the recess in the heel, the upper surface of the cushion lying substantially flush with the inner bottom surface of the shoe.

While I have shown only the preferred form 15 of my invention, it should be understood that various changes or modifications may be made within the scope of the appended claim without departing from the spirit of the invention.

I claim:

The combination with a shoe and a heel, said heel having a centrally disposed recess with its lower surface shaped as a portion of a sphere and with its upper margin shaped as a cylindrical rim, of a resilient pad mounted in the recess, said pad having a spherical surface contacting with the spherical surface of the recess, said pad also being provided with a cylindrical rim slidably mounted in the cylindrical rim of the recess, the spherical surface of the pad being provided with two intersecting grooves that cooperate with the recess wall for forming air conveying conduits, the grooves also receiving portions of the pad when the latter is compressed thereby permitting a more ready depressing of the pad, and the recess rim guiding the pad rim during the compressing and expanding of the pad.

WILLIAM J. DWYER. 40
